(57) **CLAIM**

The ornamental design for a safety bumper for a trailer tailgate, as shown and described.

DESCRIPTION

FIG. 1 is an isometric bottom view of the safety bumper for a trailer tailgate in a state of use; the broken lines illustrating a trailer tailgate frame represent environment that forms no part of the claim;

FIG. 2 is an isometric top view of the safety bumper for a trailer tailgate of FIG. 1;

FIG. 3 is an isometric bottom view thereof;

FIG. 4 is a top view thereof;

FIG. 5 is a front view thereof;

FIG. 6 is a bottom view thereof; and,

FIG. 7 is a right side view thereof, the left side view being a mirror image thereof.
